UNITED STATES PATENT OFFICE

2,672,709

TOY VEHICLE LIFT

Max Ernst, Nurnberg, Germany

Application April 24, 1951, Serial No. 222,537

7 Claims. (Cl. 46—202)

1

There are already known mechanical toys in which vehicles are elevated by lifting means, pushed out therefrom, and then run back downwards on a sloping curved track to the starting point, after which the game is repeated.

These toys are, as a result of their large size and as a result of their heavy construction, not to be recommended for a child, and are also costly in manufacture.

In contrast to these known models, the invention is characterised in that, by means of a spring drive motor with round-ended cam disc, two oppositely-lying lifting means, joined together by a lever, inserted in housings and having vehicles, are moved up and down, whereby the one lifting means in its highest position pushes out one vehicle, which rolls down a sloping curved track to the bottom and there is engaged by a second lifting means which lifts it to the top and pushes the vehicle out again, whereupon the latter is led on a sloping running rail to the first lifting means. Such a toy can be made small and is cheap to manufacture.

In the drawing the invention is shown in one embodiment by way of example. In this drawing:

Fig. 1 is a front elevation of the toy with a forward cover plate removed with parts shown in section.

Fig. 2 is a top plan view.

Fig. 3 is a fragmentary top plan view of the curved track and

Fig. 4 is the toy vehicle itself in section.

Into a removable base plate 1 is inserted a wall 2 which can be terminated by the two right angled erections positioned opposite each other, which serve as housings 3 and 4 for the lifting means, and which are provided with passage openings 5 and 6.

Inside the housings 3 and 4 are firmly inserted guide rods 7 and 8. To these guide rods are movably secured lifting means 11 and 12 having slots 9 and 10. The lifting up of the lifting means results from a spring drive mechanism 13. To the wall 2 is fastened the spring drive mechanism 13 which is on its rear side provided with a disc 14 with peg 15. The wall carries also double-armed levers 17 and 18 which are rotatable about an axle 16. The lever 17 runs downwardly to the lifting means 11 and is provided with a peg 19 which engages in the slot 9 of the lifting means 11 and which can be pushed in the slot.

The lifting means is thereby carried upwardly. The other lever 18 likewise comprises a slot 20

2

in which the peg 15 of the disc 14 engages. Because of the rotation of the disc 14 the peg 15 moves itself in the slot 20 of the lever 18 and pushes this latter forwardly. The lever 17 is thereby moved upwardly and engages the lifting means 11 by its peg 19. To the wall 2 there is also fastened a plate 21 which is provided with a bolt 22. About this bolt 22 there can be rotated a lever 24 provided with a slot 23, and which lever extends down to the lifting means 12. The end of the lever 24 above the lifting means 12 is offset as at 24^a with a leg 24^b depending from the offset and which leg carries at the end a peg 25 that is inserted in the slot 10 of the lifting means 12. The coupling of the lever 24 results from a peg 26 fastened to the lever 17, and which lies in the slot 23 of the lever 24. To the wall 2 is fastened another sloping rail track 27 which joins together the two lifting means 11 and 12. On the outside of the lifting means housings 3 and 4 are provided platforms 28 at the two passage openings 5 and 6, into which is pressed a curved track 29 which runs obliquely downwards. On this curved track 29 there rolls a vehicle for instance a car 30. Because of the narrow curves of the track 29 and the lightness of the car 30 this latter cannot run off but turns with the track and remains on it. In order to assist it there is at the inside of the car 30 a ball 31 rotatably inserted and free to move in all directions and which protrudes somewhat through the bottom of the car and, due to its weight and being in contact with the wheels of said car, moves it forwardly and easily overcomes the narrow curves of the track.

The functioning of the above-described toy is as follows:

After the spring-drive mechanism has been operated, it moves the disc 14. The peg 15 of the disc 14 then moves in the conically tapered slot 20 of the lever 18 and carries the same forwardly. Thereby the other lever 17 is lifted up and by its peg 19 carries the lifting means 11 upwardly to the passage opening 5. The car 30 resting on the lifting means and carried up therewith is then pushed through the opening 5 and rolls out on the sloping curved track 29 down to the opening 6 of the other lifting means 12. In order to achieve the pushing out of the car 30 from the lifting means there is inserted in a movable manner a running rail 32 which comprises a downwardly extending nose 33 which passes through a slot of the lifting means 11 and is rotatably held therein. To the under side of the lifting means 11 are fastened two lugs 33' through which an axle

34 passes and which axle is provided with a lever 35 that protrudes through an opening 36 of the lifting means 11 for contact with the guide rail 32. The axle 34 is provided with a rearwardly directed strip 37 which, at the top position of the lifting means, pushes against a stop 38 and is pressed downwardly. The rotatable lever 35 is thus moved upwardly and tilts one side of the guide rail 32 upwardly, causing the car to roll down on the curved track 39. Simultaneously with this movement, the lever 24, which is coupled to the peg 26 of the lever 17, is also carried with and moved in the slot 23. The peg 25 of the lever 24 thereby carries with it the lifting means 12 upwardly to the passage opening 6 so that the 15 car 30 can run on running rails 39. The disc 14 thereby moves further until the peg 15 comes to the broadened portion of the slot 20 of the lever 18. At this moment, both levers 17 and 18 fall 20 downwardly and carry with them the lifting means 11 and 12. The car 30 is now on the running rails 39 of the lifting means 12 and is taken downwardly therewith. To the wall 2 is fixed a device 40 with an upstanding nose 41. This device 41 lifts up the running rails 39 so that the 25 car starts to roll and runs on the steep running rail 27. The car 30 can now run into the oppositely lying lifting means. The lifting up, the pushing out, the rolling down and the exit and entrance from and into the lifting means are then 30 performed as described precedingly until the spring-drive mechanism has run out. To the right-hand lifting means housing 4 is fastened an angle plate 42 rotatably about an axis and which closes the entrance opening 6 so that the vehicle 30 which has rolled off the curved track 29 can firstly pass into the lifting means 12 when this plate 42 is lifted high and the lifting means 35 is already standing at the entrance opening. This is achieved in that the lever 24 has a nose 43 which, when the lever 24 is raised, pushes the angle plate 42 upwardly. When the lever 24 falls, the plate 42 also falls downwardly again by its own weight and closes the entrance opening.

What I claim is:

1. In a mechanical toy vehicle lifting device, an elongated platform, vertical guide means at each end of the platform, a lift for toy vehicles reciprocably mounted on each of said guide means, a support rising from said platform, an inclined and fixed track leading from the upper part of one of said guide means to the lower part of the other guide means, a second fixed and inclined track leading from the lower part of said last mentioned guide means to the lower part of the first mentioned guide means, and clockwork driven means mounted on said support and connected to and reciprocating the lifts into and out of horizontal alinement with the ends of said tracks.

2. In a mechanical toy vehicle lifting device, an elongated platform, vertical guide means at each end of the platform, a lift for toy vehicles reciprocably mounted on each of said guide means, a support rising from said platform, an inclined and fixed track leading from the upper part of one of said guide means to the lower part of the other guide means, a second fixed and inclined track leading from the lower part of said last mentioned guide means to the lower part of the first mentioned guide means, clockwork driven means mounted on said support and connected to and reciprocating the lifts into and out of horizontal alinement with the ends of said tracks, and

means for causing movement of toy vehicles from said lifts upon alinement of the respective lifts and upper ends of the tracks.

3. In a mechanical toy vehicle lifting device, an elongated platform, vertical guide means at each end of the platform, a lift for toy vehicles reciprocably mounted on each of said guide means, a support rising from said platform, an inclined and fixed track leading from the upper part of one of said guide means to the lower part of the other guide means, a second fixed and inclined track leading from the lower part of said last mentioned guide means to the lower part of the first mentioned guide means, clockwork driven means mounted on said support and connected to and reciprocating the lifts into and out of horizontal alinement with the ends of said tracks, a tiltable platform on each of said lifts, tilting mechanisms under said platforms, a stop for actuating said mechanisms carried by said guide means and engaging the respective mechanisms adjacent the upper ends of said tracks.

4. In a mechanical toy vehicle lifting device, an elongated platform, vertical guide means at each end of the platform, a lift for toy vehicles reciprocably mounted on each of said guide means, a support rising from said platform, an inclined and fixed track leading from the upper part of one of said guide means to the lower part of the other guide means, a second fixed and inclined track leading from the lower part of said last mentioned guide means to the lower part of the first mentioned guide means, a clockwork mounted on said support, a disk rotatably driven by said clockwork, a pair of levers pivotally connected to said support and each having an arm operatively connected to a respective lift, and means actuated by the rotation of said disk and causing oscillation of the levers.

5. In a mechanical toy vehicle lifting device, an elongated platform, vertical guide means at each end of the platform, a lift for toy vehicles reciprocably mounted on each of said guide means, a support rising from said platform, an inclined and fixed track leading from the upper part of one of said guide means to the lower part of the other guide means, a second fixed and inclined track leading from the lower part of said last mentioned guide means to the lower part of the first mentioned guide means, a clockwork mounted on said support, a disk rotatably driven by said clockwork, a pair of levers pivotally connected to said support and each having an arm operatively connected to a respective lift, means actuated by the rotation of said disk and causing oscillation of the levers, and means for causing movement of toy vehicles from said lifts upon alinement of the respective lifts and upper ends of the tracks.

6. In a mechanical toy vehicle lifting device, an elongated platform, vertical guide means at each end of the platform, a lift for toy vehicles reciprocably mounted on each of said guide means, a support rising from said platform, an inclined and fixed track leading from the upper part of one of said guide means to the lower part of the other guide means, a second fixed and inclined track leading from the lower part of said last mentioned guide means to the lower part of the first mentioned guide means, a clockwork mounted on said support, a disk rotatably driven by said clockwork, a pair of levers pivotally connected to said support and each having an arm operatively connected to a respective lift, means actuated by the rotation of said disk and causing

oscillation of the levers, a tiltable platform on each of said lifts, tilting mechanisms under said platform, a stop for actuating said mechanisms carried by said guide means and engaging the respective mechanisms adjacent the upper ends of said tracks.

7. In a mechanical toy vehicle lifting device, an elongated platform, vertical guide means at each end of the platform, a lift for toy vehicles reciprocably mounted on each of said guide means, a support rising from said platform, an inclined and fixed track leading from the upper part of one of said guide means to the lower part of the other guide means, a second fixed and inclined track leading from the lower part of said last mentioned guide means to the lower part of the first mentioned guide means, a clockwork mounted on said support, a disk rotatably driven

5 by said clockwork, a bell-crank lever pivoted at its angle to said support, said lever having a short arm provided with pin and slot connection with the disk and a long arm having pin and slot connection with one of said lifts, a second lever pivoted at one end to the support, the free end of said second lever having pin and slot connection with the other lift, and a pin and slot connection between the second lever and the long arm of the bell crank lever.

10 MAX ERNST.
